UNITED STATES PATENT OFFICE.

ALBERT A. HODGKINS, OF BRIDGEPORT, CONNECTICUT, ASSIGNOR TO THE AMERICAN FABRICS COMPANY, A CORPORATION OF CONNECTICUT.

DESIGN FOR EMBROIDERY TRIMMING.

Application filed February 3, 1922. Serial No. 520. Term of patent 7 years.

To all whom it may concern:

Be it known that I, ALBERT A. HODGKINS, a citizen of the United States, residing at Bridgeport, county of Fairfield, State of Connecticut, have invented a new, original, and ornamental Design for Embroidery Trimming, of which the following is a specification, reference being had to the accompanying drawing, forming a part thereof.

The figure is a plan view of a piece of embroidery trimming showing my new design.

I claim:

The ornamental design for embroidery trimming substantially as shown.

In testimony whereof I affix my signature.

ALBERT A. HODGKINS.
